TELEVISION RECEIVING ANTENNA

Joseph Y. Resnick, Ellenville, N. Y., assignor to
Channel Master Corporation, Ellenville, N. Y.,
a corporation of New York

Application February 15, 1950, Serial No. 7,944

Term of patent 3½ years

(Cl. D26—14)

To all whom it may concern:

Be it known that I, Joseph Y. Resnick, a citizen of the United States, and a resident of Ellenville, county of Ulster, State of New York, have invented a new, original, and ornamental Design for a Television Receiving Antenna, of which the following is a specification, reference being had to the accompanying drawing, forming part thereof.

In the drawing:

Fig. 1 is a front elevational view of a television receiving antenna, with the telescoping dipoles thereof in closed position, embodying my new design;

Fig. 2 is a front elevational view thereof, with the dipoles in extended V-shape position, and
Fig. 3 is a plan view thereof.

Fig. 4 is a left-hand side view of the television receiving antenna.

Fig. 5 is a right-hand side view thereof.

I claim:

The ornamental design for a television receiving antenna, as shown.

JOSEPH Y. RESNICK.
